(57) **CLAIM**

The ornamental design for a candle, as shown and described.

DESCRIPTION

FIG. 1 is a perspective view of a candle in accordance with a preferred embodiment present invention.

FIG. 2 is a side view of the candle of FIG. 1.

FIG. 3 is a front view of the candle of FIG. 1.

FIG. 4 is a top view of the candle of FIG. 1.

FIG. 5 is a bottom view of the candle of FIG. 1.

FIG. 6 is a front view of a second preferred embodiment of a candle in accordance with the present invention; and, FIG. 7 is a side view of the embodiment of FIG. 6.

The broken line structure showing in FIGS. 2 and 6 is for illustrative purposes only and forms no part of the claimed design.
